UNITED STATES PATENT OFFICE.

SAMUEL MORRIS LILLIE, OF PHILADELPHIA, PENNSYLVANIA.

EVAPORATING APPARATUS.

Application filed July 24, 1922. Serial No. 577,054.

To all whom it may concern:

Be it known that I, SAMUEL MORRIS LILLIE, a citizen of the United States, residing at 4804 Springfield Avenue, in the city of Philadelphia, in the county of Philadelphia and State of Pennsylvania, have invented new and useful Improvements in Evaporating Apparatus, of which the following is a specification.

10 My invention relates to and embodies improvements upon my mechanical film evaporator which is extensively known as the "Lillie mechanical film evaporator" or simply "Lillie evaporator". Following the mode of operation of this apparatus, the liquid under evaporation lies in the shell of the evaporator below the heating surfaces, which surfaces are kept wet with the liquid in films by means of a circulating pump 15 and connections between it and the evaporator shell which draw from the liquid in the bottom of the evaporator shell and shower it over the heating surfaces down which it flows in films back into the space 20 below after completing a cycle of the constant circulation which is maintained over the heating surfaces by the circulating pump and its connections.

The apparatus described in the following specification and illustrated in the accompanying drawings provides particular methods of taking the vapors of evaporation from the nest of evaporating tubes which gives a more free and easy escape 35 for the vapors than has hitherto been the case, and permits of valuable advantages in the arrangement and construction of the apparatus.

Referring to the drawings—

40 Figure 1 is partly a plan and partly a horizontal section through the line X—Figure 2 and line Y—Figure 3.

Figure 2 is mostly a middle vertical section of one arrangement of my improved evaporator, along the line W—Figure 1 and line Z—Figure 3.

Figure 3 is an end elevation looking at the door 16 but with the left half broken away to show a transverse vertical half section along the lines V—Figure 2—and lines V—Figure 1 and Figure 5.

Figure 4 shows a detail of an evaporating tube, as employed in the construction of Figures 1 to 3, inclusive, i. e., which constructions are intended for land service.

Figure 5 is in part a plan and in part

a horizontal section through an evaporator intended for marine service.

Referring to the drawings, 1, is the inclosing case or shell of the evaporator made of any suitable material. It is shown cylindrical in horizontal cross section but may be elliptical, rectangular or of other shape. It is closed at the top by the head 2, indicated with a vapor escape opening 3 with connected vapor pipe, see Figure 3. The case is closed by a dish shaped bottom 5, which has a liquid discharge opening 6—to which connects the suction line of the circulating pump 7. This pump is driven by motor or other means not indicated.

In the interior of the evaporator shell extending from one side of it nearly to the opposite is a nest, 8, of evaporating tubes, having in the case illustrated rectangular vertical and horizontal cross sections, and so proportioned and located in the evaporator shell as to leave below it a considerable liquor and vapor space, 9, and on each side of the nest vapor spaces, 10, and 17, respectively, and above the tubes a vapor collecting chamber, 12, with which the side spaces 10 and 11, also the space 9 below the tubes, space 4 above the tubes, and the space 4^a in front of the tubes connect. In this collecting chamber the vapors which escape from the nest of tubes collect preparatory to leaving the evaporator, all as hereinafter described. The tubes forming the nest are parallel to each other and are arranged in vertical and horizontal rows with tubes in the latter rows covering and breaking spaces with each other. Between the horizontal rows transverse horizontal spaces, shown in Figures 2 and 3, are left which form vapor passages unobstructed by tubes between the interiors of the tube nests and surrounding vapor spaces. Thus disposed, the tubes of each row, excepting the lower row, serve to deflect or direct the falling liquid onto the tubes of the row next below but leave free horizontal vapor passages or spaces between the rows of tubes. The greater the vertical width of these horizontal passages, the less will be the pressure difference between the inner parts of the tube nests and the vapor spaces surrounding the tube nests. At one end the nest of tubes extend into a neck, 13, formed on and projecting horizontally from the shell, to the

105 110

end of which neck is attached the steam chamber, 14, with a transverse vertical tube plate, 15, separating the interiors of the neck and chamber. The steam chamber is closed opposite to the tube plate by a hinged door, 16, and it has a somewhat larger cross area than the area of the tube plate—and where it joins the neck, 13, forms a shoulder or flange, 17, properly machined against which the tube plate is bolted steam tight. The steam chamber extends sufficiently below the tube plate to form a proper pocket, 18, for condensate, from which the condensate escapes through a pipe, 19, guarded by a suitable steam trap as shown. This trap may be located in the said pocket of the steam chamber. Opposite the tube plate, the vapor chamber is formed with a door, 20, which when opened uncovers a somewhat greater area than that of the tube plate, sufficient to permit access to, and in some cases the entrance of a man above, the tube nest.

The evaporating tubes open through the tube plate into the steam chamber and are expanded in the tube plate without having been annealed, the tubes (see Figs. 1 and 2) are supported entirely by the tube plate. The ends of the tubes away from the tube plate are not supported or held in any way, and the end of each tube is closed and is provided with a small air vent plug, see Figure 5, in which is shown the free end of a tube such as have been used in "Lillie evaporators" and such as are used in the nest of tubes illustrated in Figures 1-2 and 3 for land installations. The tubes incline slightly downwards towards the tube plate so that the steam condensate will flow back into the steam chamber. The spaces or passages around the unsupported ends of the tubes connect all the intertwine spaces, vertical as well as horizontal, with the vapor space 4^a between the ends of the tubes and the door 20.

Above the nest of tubes there is supported in any suitable way a perforated distributing plate 21—this plate is horizontal and nearly covers the entire cross area of the tube nest. It extends into the neck, 13, nearly to the tube plate. At the other end, the edge of the perforated plate touches the edge of the cross rib 22 attached to the door, 20. Between the plate 21 and the upper row of the tube nest, 8, is a vapor space, 4, which connects on either side with vapor spaces 10 and 11 respectively and thence to the collecting chamber 12, which is also the case with the vapor space, 9, below the nest of tubes and the space 4^a which faces the free ends of the tubes. Towards the sides, the perforated plate extends practically to a system of baffles 23 and 24 hereinafter described. The discharge pipe, 25, of

circulating pump 7 delivers through the inside connecting pipe, 25^a, upon the perforated plate 21—at a point located about symmetrical with respect to the two side edges and the two end edges of the plate. 70

On each side of the nest of tubes is an arrangement of baffles, at 23 on one side and at 24 on the other side of the nest. Each baffle consists of two parallel rows of vertical metal I bars, which bars in 75 each row stand on end with their webs in line and parallel to the length of the tube nest. The I bars in each row are spaced a short distance apart, with the bars in the two rows breaking interspaces with 80 each other. The two rows of I bars are quite close together, so that the two rows mesh with each other so to speak, and vapors passing through the interspaces of one row will be baffled by the webs of the 85 other row. The baffles are supported on each side of the nest upon a rib or plate, 26, which extends outward from the side of the shell and parallel to the tubes of the nest. The rib on one side of the tube 90 nest is shown at 26. On the other side of the tube nest is a similar rib which serves a similar purpose. Each rib supports the baffle elements which stand upon it between two ribs. The upper ends of 95 each baffle system rest between the ribs of a horizontal I bar, 27, which extends from front to back of the evaporator case and is at an elevation about the same as the perforated plate 21—an edge of which 100 extends to the baffles just below the lower edge of the I bar, 27.

It is apparent that the nest of evaporator tubes and the vapor spaces 4 and 9 are all entirely surrounded and separated 105 from the vapor spaces 10, 11 and 12, within the shell, by the baffles 23 and 24—perforated plate 21, rib 22, on door 20 and the ribs or plates 26—which support the baffle, so that the only connections is by the tortuous passages through the baffles. 110

On each side above the baffle sets 23 and 24, and resting on the I beam 27—are other vertical baffle sets similar to 23 and 24—one of which sets 24^a is shown. Each of 115 these extends from a horizontal I beam, 27 to the roof 2 of the evaporator shell where the elements rest between the two ribs 28—28, with sufficient play upwards; so that the baffle elements may be raised away 120 from the I bar below and removed from the evaporator through the opened door 20 or other suitable opening in the shell—the elements of the lower baffles 23 and 24—may be removed through the door way 125 when the door is opened.

The feed of the liquid to be evaporated in the evaporator is through the float operated valve 29; the concentrated liquid is delivered away by the circulating pump. 130

7 through the discharge nozzle 30. The operation of the apparatus illustrated in Figures 1 to 4, inclusive, may be described as follows:

- 6 A charge of liquid having been delivered into the bottom of the evaporator through the float valve 29, the circulating pump 7 is put in service which results in the liquid being delivered in large quantities through 10 the connecting pipes 25 and 25^a on to the perforated distributing plate 21. The impact of the liquid upon the plate causes the liquid to spread over the entire surface of the plate and to shower through the perforations in the plate upon the nest of tubes below, down and over which the liquid flows as indicated in Figures 2 and 3.
- If now steam be delivered into the steam chamber 14 through the nozzle marked 20 "Steam inlet", the steam passes into the evaporating tubes and will cause evaporation from the liquid circulating over the tubes with a condensation of the steam inside the tubes and with the collection of the air or 25 other gases, which may have been contained in the entering steam, at the free tube ends from which gases escape into the interior of the evaporator through an air vent in each tube end, as indicated in Figure 4 "Tube 30 ends". The condensate from the steam flows back from the tube into the steam chamber, 14, and away from the latter through the discharge pipe 19 as controlled by a steam trap of some suitable make as indicated in the 35 drawings.

The vapors resulting from the evaporation escape from the tube nest from all sides of the nest with the exception of the side at the tube plate. They escape from each side into 40 the adjacent spaces and thence through the baffles into the passages 10 and 11. Some of the vapors escape into the space 4 above the tubes and under the perforated plate, 21, and thence escape to the side spaces. Some also 45 escape into the space 9 below the nest and above the liquid in the bottom of the evaporator and thence into the side spaces and they escape from the tube nest through the longitudinal inter tube spaces into the space, 50 4^a, between the free ends of the tubes and the door 20 and thence as indicated by the arrows pass around into the side spaces. All the vapors escaping from the five sides of the tube nest pass through the vapor baffles 55 into the spaces 10 and 11 and the same pass upwards and through the upper set of baffles, as 24^a, into the collecting chamber or space above and from it escape from the evaporator through the opening marked "Vapor 60 outlet".

The vapor current away from the tube nest at any point is comparatively slow and consequently has but slight tendency to carry particles of liquor entrained in it, so that even if no baffles are used, and the vapor

were allowed to merely pass into the side passages and up through the same into the upper or collecting chamber 12, without any obstruction by intervening baffles such as 24 and 24^a, there would be very little entrained liquid in the vapor passing away through the "vapor outlet" during normal operation of the evaporator. Many natural fresh waters contain very little salts in solution, say 1% of that in sea water. In the evaporation of these the baffles could be omitted and also the ledge 22 on the door 20, Fig. 2 could be omitted in which latter case the vapors passing into the space 4^a from around the ends of the tubes would pass upwards 80 into the collecting chamber 12.

A sudden drop in pressure in the interior of an evaporator causes ebullition through all the particles of liquid in the evaporator and is likely to cause considerable entrainment in the vapor leaving a nest of tubes at the instant of the drop, and in the case of submerged tube evaporators where the liquid is boiling in mass, the entrainment at the time of a sudden drop in pressure is very heavy. In the construction shown in the drawings all the entire nest of tubes and all the liquid lying in the bottom of the evaporator is separated from the vapor spaces and from the collecting chamber 12 by the baffles 24, 24^a, etc., and otherwise as described in the specifications, so that no vapor can away from the circulating liquid or, from the liquid in mass below the tubes, which does not pass through the baffles before it enters the collecting chamber, 12, and passes from the "vapor outlet", so that even in the event of a sudden drop in pressure, there is likely to be little entrainment in the vapors leaving the evaporators.

The construction of the cylindrical shell of the evaporator with a projecting neck, 13, with the steam chamber at the end of the same, permits a smaller diameter for the cylindrical case for a given area of heating surface in the tube nest, which results in an economy of space occupied by the evaporator when constructed with a cylindrical case.

In Figure 5 the evaporating tubes at the end away from the steam chamber are not closed, but they open into a floating head 31. During the process of evaporation in the construction of Figure 5, the incondensable gases which come in with the steam, collect as above at the ends of the tubes away from the steam chamber. In the case of the floating head, the air passes through the perforations in a septum plate, 31, and into the space 32. The incondensable gases may be taken away from this space through the vent pipe, 33, which opens into the space 32 and extends along an evaporating tube to the steam chamber and through and away from it, to any exhausting apparatus, or if

the pressure is greater than the atmosphere, then away against the pressure of the latter. These gases laden with vapor may be used for heating purposes. Or instead of this 5 vent pipe, the space 32 may be vented directly into evaporator shell through a little vent indicated by 34.

The construction of Figure 5 is suited to use on shipboard where the evaporator is 10 subjected to the rolling motion of the ship. For the purpose of preventing the swashing of the sea water being evaporated lengthwise of the nest of tubes, transverse vertical surge plates, 35, are placed in the space underneath the tubes.

Figure 1 and also Figure 5 indicate a construction of film evaporator in which the nest of tubes is contained in a longitudinal shell, which shell has above the tube 20 nest an enlargement 12 intermediate to the ends of the tubes, to form a chamber into which the vapors of evaporation flow from the protruding sections of the longitudinal shell and from which enlargement the vapors escape from the evaporator.

By the expression "film evaporator," as employed in the following claims, is meant an evaporator in which evaporation is obtained by delivering or showering the liquid 30 to be evaporated in limited quantities on to the top of an aggregation or nest of heating surfaces so arranged that the liquid showered upon it will fall downward from element to element of the heating surfaces 35 and keep them thoroughly wetted and finally fall from the nest of tubes to a receptacle below from which receptacle evaporating liquid is recirculated over the heating surfaces continuously. The elements of 40 the "heating nest" are, by some heating agent, maintained at a temperature above the boiling point of the circulated liquid at the pressure existing in the spaces surrounding the heating surfaces. In the 45 specification steam is mentioned as the "heating" agent, but other agents may be used—hot gases and electricity are examples. In the specifications and drawings, the heating nest is composed of an aggregation of parallel horizontal tubes supplied with steam at one end of the nest of tubes from a steam chamber common to all the 50 tubes—other arrangements of the heating surfaces may be employed.

55 I claim the following as of my invention, viz:

1. In a film evaporator a shell; a nest of tubular heating elements so supported within the shell and having such dimensions and location as to provide spaces within the shell surrounding the nest; vapor baffle walls enclosing the nest and dividing the spaces surrounding the nest into a nest compartment and outer compartments; means 60 for supplying the tubular heating agents internally with a heating agent; distributing means above the nest of tubular heating elements within the enclosing vapor baffle walls; means for delivering a liquid to the distributing means; vapor passages 70 through the vapor baffle enclosing walls between nest compartment and outer compartments; and vapor escapes for the outer compartments.
2. In a film evaporator a shell; a nest of tubular heating elements so supported within the shell in a lower portion thereof and having such dimensions and location as to provide spaces surrounding the nest within the shell; means for supplying the tubular 80 heating elements internally with a heating agent; a perforated septum plate located above the nest of tubular heating elements and serving to divide the interior of the shell essentially into a lower chamber containing the heating elements and a vapor collecting chamber above; means for delivering a liquid to be evaporated upon the said perforated septum plate and through its perforations onto the top of the nest of 90 heating elements; vertical vapor baffle walls enclosing the collecting chamber above the perforated septum plate, vapor passages through these walls and communicating with the spaces below the septum plate; and 95 a vapor escape for the collecting chamber.
3. In a film evaporator a shell; an enclosure within the shell formed by approximately vertical vapor baffle enclosing walls so located within the shell as to leave outer 100 spaces between the walls and the sections of the shell facing the walls; a nest of tubular heating elements in a lower part of said enclosure; means for supplying the interior of the tubular heating elements with a 105 heating agent; distributing means above the said nest of heating elements and adapted to shower a liquid over the heating elements, and means for delivering the liquid to be evaporated to the distributing means; 110 vapor passages through the vapor baffle enclosing walls between the tube nest enclosure and the said outer spaces; a collecting chamber above the distributing means; vapor communications between the collecting 115 chamber and the said outer spaces; and a vapor outlet for the collecting chamber.
4. In a film evaporator a containing shell; an enclosure within the shell having its sides formed by approximately vertical 120 vapor baffle walls each extending nearly to the roof of the shell and nearly to the floor of the same, the baffle walls being so located within the shell as to form outer compartments between the shell and said walls and 125 a nest of tubular heating elements supported in the said enclosure in the lower part thereof; distributing means located above the nest of heating elements for distributing and showering liquid over the said nest and ex- 130

tending to the inner surfaces of the enclosing walls to form a tube nest chamber below and a vapor collecting chamber above said distributing means within the enclosing walls; means for delivering a liquid to the distributing means; vapor passages through the vapor baffle enclosing walls between the tube nest chamber and the said outer compartments; vapor passages through the enclosing walls between the collecting chamber and the said outer compartments; and a vapor outlet for the collecting chamber.

5. In a film evaporator an inclosing shell; a nest of substantially horizontal and parallel spaced heating tubes; so supported within the shell in a lower portion thereof as to provide spaces within the shell on each side of the nest of tubes and an upper space above the tubes, the tubes at one end opening 10 through a tube plate into an inclosed steam chamber separated from the interior of the shell by the tube plate, the tubes at the other end away from the tube plate being closed and facing an end space in the shell, the intertube spaces communicating with the said end space; a steam supply inlet to the steam chamber; distributing means within the shell in the lower part of the space above the nest 15 of heating tubes and adapted to shower a liquid over the nest of tubes, with means for delivering a liquid to be evaporated to the distributing means; the spaces at the sides of the nest of tubes communicating with the upper space above the distributing means 20 therein; and the said end space communicating with the upper space above the distributing means and a vapor outlet for the said upper space above the distributing means.

6. In a film evaporator a vertical shell; a neck projecting horizontally from and opening into the vertical shell; an enclosed steam

chamber at the end of the neck away from the shell, with a tube plate dividing the interior of the steam chamber from the interior of the neck; a nest of substantially horizontal and parallel spaced heating tubes supported within the neck, the tubes at one end opening through the tube plate into the steam chamber and at the other end extending into the vertical shell; a steam supply 45 inlet to the steam chamber; distributing means within the vertical shell above the nest of tubes and extending into the neck, adapted to shower a liquid over the nest of tubes within the neck and the vertical shell; means for delivering a liquid to be evaporated to the distributing means; vapor spaces 50 around the nest of tubes within the neck, extending to and opening into the vertical shell; and a vapor outlet for the vertical shell.

7. In a film evaporator; an inclosing longitudinal horizontal shell; a nest of substantial horizontal and parallel spaced heating tubes so supported within the shell as to have a surrounding space between the nest 65 of tubes and the inclosing shell, and means for supplying the tubes with a heating agent; an upwardly extending portion of the shell above the nest of tubes and shorter than the tubes, said portions being adapted 70 to serve as a collecting chamber for vapors; distributing means within the inclosing longitudinal shell above the heating tubes adapted to shower a liquid over the nest of tubes throughout the length of the nest of 75 tubes within the shell; vapor passages connecting and adapted to convey vapors of evaporation from the portions of the shell beyond the limits of the collecting chamber 80 to the chamber; a vapor outlet for the vapor chamber.

SAMUEL MORRIS LILLIE.
